To all whom it may concern:

Be it known that I, Pierre Stroobants, a citizen of Belgium, residing at 53, Rue de l'Agrafe, Anderlecht-Brussels, Belgium, have invented a new, original, and ornamental Design for a Magnetic Recording Dictating Machine, of which the following is a specification, reference being had to the accompanying drawing, forming a part hereof.

Fig. 1 is a perspective view of the machine; and Fig. 2 is a rear view thereof.

The side not shown in Fig. 1 is substantially the same as the side shown.

I claim:

The ornamental design for a magnetic recording dictating machine, as shown and described.

PIERRE STROOBANTS,
